ABSTRACT

A *chrysanthemum* plant named 'Zanmumadore Yellow' characterized by its medium sized blooms with yellow ray florets and dark centers and prolific branching; natural season flowering date October 2 (week 41); blooming for a period of 5 weeks.

3 Drawing Sheets

1

Botanical designation: *Chrysanthemum x morifolium* Ramat.
Cultivar denomination: 'Zanmumadore Yellow'.

RELATED CULTIVARS

The new plant is a flower color mutant of 'Zanmumadore' (unpatented)

BACKGROUND OF THE INVENTION

The present invention relates to a new and distinct cultivar of *chrysanthemum* plant, botanically known as *Chrysanthemum x morifolium* Ramat, commercially known as a garden mum, and hereinafter referred to by the cultivar denomination 'Zanmumadore Yellow'. 'Zanmumadore Yellow' is a product of a breeding and selection program which had the objective of finding flower color mutants from existing parent plants. The new plant comprises a whole plant mutant of the parent *chrysanthemum* named 'Zanmumadore' (unpatented). Plants from the new cultivar 'Zanmumadore Yellow' differ from plants of the parent in the color of the ray-florets. The ray-florets of the parent are pink, while those of the new plant are yellow.

In order to obtain color mutants, unrooted cuttings of the parent plant were irradiated in April 2014 at Ziekenhuis, Rotterdam, the Netherlands, with gamma radiation at a dose of 15Gy. These treated cuttings were then planted in a controlled environment (greenhouse) in Rijsenhout, the Netherlands. In this population of planted cuttings, the new cultivar was discovered as a natural flower color mutant in October 2014 by Sjoukje Heimovaara. The first act of asexual reproduction of 'Zanmumadore Yellow' was accomplished when after planting of the 'Zanmumadore Yellow' as a motherplant in December 2014, vegetative cuttings from this 'Zanmumadore Yellow' were taken and propagated further in Rijsenhout, the Netherlands. In summer, about 6-8

2

days are needed to initiate roots in cuttings of the new cultivar, after another 5 days rooted plants are formed. The new cultivar has been found to retain its distinctive characteristics through successive asexual propagations.

BRIEF DESCRIPTION OF THE DRAWINGS

The present invention of a new and distinct variety of *chrysanthemum* (of about 22 weeks) is shown in the accompanying drawings, the color being as nearly true as possible with color photographs of this type.

FIG. 1 shows a plant of the cultivar in full bloom.

FIG. 2 shows the various stages of blooms of the new cultivar.

FIG. 3 shows the various stages of foliage of the new cultivar.

DESCRIPTION OF THE INVENTION

The observations and measurements were gathered from plants in the period of 19 to 25 weeks of age grown outdoors in Rijsenhout, the Netherlands, under natural day length and temperature and planted in week 22 in 2017. The natural blooming date of this crop was October 2 (week 41). The average height of the plants was 25-30 cm. No growth retardants were used. No tests were done on disease or insects resistance or susceptibility. No tests were done on cold or drought resistance. This new variety produces medium sized blooms with yellow ray florets and a dark center blooming for a period of five weeks.

From the cultivars known to the inventor the most similar existing cultivars in comparison to 'Zanmumadore Yellow' is its parent 'Zanmumadore' and 'Zanmumadore Orange'. When 'Zanmumadore', 'Zanmumadore Yellow' and 'Zanmumadore Orange' are being compared the following dif-

ferences are noticed: ray floret color in 'Zanmumadore' is pink, yellow in 'Zanmumadore Yellow' and bronze in 'Zanmumadore Orange'.

The following is a description of the plant and characteristics that distinguish 'Zanmumadore Yellow' as a new and distinct variety.

The color designations are taken from the plant itself. Accordingly, any discrepancies between the color designations and the colors depicted in the photographs are due to photographic tolerances. The color chart used in this description is: The Royal Horticultural Society Colour chart, sixth edition, 2015.

TABLE 1

Botanical Description of <i>Chrysanthemum × morifolium</i> Ramat. 'Zanmumadore Yellow'	
Bud	
Size:	Small; cross-section 5 mm, height 4 mm
Shape:	Round
Texture:	Pubescent
Outside color:	Greyed-green 191A
Phyllaries	
Number:	24, arranged in 3 rows
Shape:	Elliptic
Apex:	Acute
Base:	Truncate
Margin:	Entire
Color:	Upper side: Green 139A Lower side: Green N138C
Length and width:	0.6-0.8 mm; 2-4 mm
Texture:	Pubescent
Inflorescences	
Type:	Double
Height:	13 cm
Diameter:	3.5-4 cm
Peduncle length:	6-7 cm
Peduncle color:	Green 138B
Peduncle diameter:	1.5 mm
Peduncle texture:	Pubescent
Peduncle strength:	Medium
Number per branch:	About 8-9 inflorescences
Duration of flowering:	5 weeks
Seeds:	Produced in small quantities, ovate, Greyed-brown 199A, length 1.5 mm, diameter 0.5 mm; texture: rough with ribs
Fragrance:	Faint <i>chrysanthemum</i> odor
Color inflorescences	
Center of inflorescence:	Immature stage: Yellow 13A; Mature stage: Yellow 13A
Color of upper side of ray florets (outer rows):	Yellow 12B
Color of lower side of ray florets (outer rows):	Yellow-orange 17B
Color of upper side ray florets (inner rows):	Yellow 10A
Color of lower side ray-florets (inner rows):	Yellow-orange 17B
Tonality from distance:	A garden mum with bronze blooms and a dark center
Color of ray florets after aging of the plant:	Yellow 10A
Ray florets	

Number of types:	2
Type:	Ligulate
Rows:	about 15
Texture:	Upper and lower side smooth
Number:	outer rows: 140; inner rows: 30
Shape:	outer rows: elliptic; inner rows: narrowly elliptic

TABLE 1-continued

Botanical Description of <i>Chrysanthemum × morifolium</i> Ramat. 'Zanmumadore Yellow'	
5	Apex: outer rows: dentate; inner rows: dentate Base: attenuate Cross-section: outer rows: flat; inner rows: concave Longitudinal axis: outer rows: straight; inner rows: straight Length of corolla tube: 3 mm 10 Diameter: corolla tube: 1 mm Ray floret margin: Entire Ray floret length (outer rows): 1.5-2 cm Ray-floret length (inner rows): 0.8-1 cm Ray-floret width (outer rows): 3 mm Ray floret width (inner rows): 1 mm Ratio length/width: Medium Disc florets Absent Receptacle
15	Color: Yellow-green 145D Shape: Domed raised Height: 3-4 mm Diameter: 4 mm Reproductive Organs
20	Androecium: Absent Pollen: Lacking Gynoecium: Present on ray florets 25 Style color: Yellow-green 154C Style length: 4 mm Stigma color: Yellow 7A Stigma width: 1 mm Ovary: Enclosed in calyx Ovary color: Yellow-green 149D 30 Plant
35	Type: Bushy Growth habit: Spherical shape Growth rate: High Height: 25-30 cm Width: 40-45 cm Stem color: Greyed-brown 199A Stem strength: Not strong Stem brittleness: Brittle Stem anthocyanin coloration: absent Internode length: 0.5-2.5 cm Length of lateral branch: From top to bottom 20-22 cm 40 Lateral branch color: Green 137 C Lateral branch, attachment: Weak Lateral branch diameter: 3 mm Lateral branch texture: pubescent with ribs Branching (average number of lateral branches): Medium with 8 breaks after pinching 45 Natural season blooming date: October 2 (week 41) in Rijnsenhout, the Netherlands. Root habits: Fine, freely branching Root color: White 155D Rooting time: 6-8 days Formation rooted plants: 12-14 days 50 Foliage
55	Leaf glossiness: Upper side: very weak Lower side: absent Leaf color: Upper side: Green 136A Lower side: Green 137A. Color mid vein: Upper side: Yellow-green 147D Lower side: Yellow-green 148D Size: Small; length 2.5-5 cm, width 0.8-2 cm Quantity (number per lateral branches): about 25
60	Shape: Elliptic to obovate Texture upper side: Sparsely pubescent Texture under side: Pubescent Venation arrangement: Pinnate Shape of margin: Serrated Shape of base of sinus between lateral lobes: Rounded 65

US PP31,021 P2

5

TABLE 1-continued

Botanical Description of <i>Chrysanthemum × morifolium</i> Ramat. 'Zanmumadore Yellow'	
Margin of sinus between lateral lobes:	Diverging
Shape of base:	Acute
Apex:	Mucronulate
Petiole attitude:	Moderately upwards
Petiole length:	0.1-0.8 cm
Petiole diameter:	3 mm
Petiole color:	Yellow-green 147D
Stipules:	present, small

6

TABLE 2

Differences with the comparison variety, when grown under identical conditions			
		'Zanmumadore'	'Zanmumadore'
		'Zanmumadore'	'Orange'
5	Color upper side ray floret-outer row	Red-purple 72C	Yellow 12B
10	Color upper side ray floret color- inner row	Red-purple 72A	Yellow 10A
15			Greyed-orange 163C
			Greyed-red 178A

I claim:

1. A new and distinct *chrysanthemum* plant named 'Zanmumadore Yellow' as described and illustrated.
